(57) **CLAIM**

The ornamental design for a glass rack for vehicles as shown and described.

DESCRIPTION

FIG. 1 is a bottom perspective view of my glass rack for vehicles as viewed from the right and rear;

FIG. 2 is a top perspective view thereof as viewed from the front and right side;

FIG. 3 is a top plan view thereof;

FIG. 4 is a bottom plan view thereof;

FIG. 5 is a left side view thereof;

FIG. 6 is a right side view thereof;

FIG. 7 is a rear view thereof;

FIG. 8 is a front view thereof;

FIG. 9 is a bottom perspective view of another embodiment of my glass rack for vehicles as viewed from the right and rear;

FIG. 10 is a top perspective view thereof as viewed from the front and right side;

FIG. 11 is a top plan view thereof;

FIG. 12 is a bottom plan view thereof;

FIG. 13 is a left side view thereof;

FIG. 14 is a right side view thereof;

FIG. 15 is a rear view thereof; and,

FIG. 16 is a front view thereof.

The broken lines shown in the drawings illustrate portions of my glass rack for vehicles that form no part of the claimed design.
